US00D881843S

(12) **United States Design Patent** (10) **Patent No.:** **US D881,843 S**
Hu (45) **Date of Patent:** **** Apr. 21, 2020**

(54) **HEADPHONES**

(71) Applicant: **SHENZHEN QIANHAI PATUOXUN NETWORK AND TECHNOLOGY CO., LTD**, Shenzhen (CN)

(72) Inventor: **Zaihui Hu**, Shenzhen (CN)

(73) Assignee: **SHENZHEN QIANHAI PATUOXUN NETWORK AND TECHNOLOGY CO., LTD**, Shenzhen (CN)

(**) Term: **15 Years**

(21) Appl. No.: **29/718,375**

(22) Filed: **Dec. 23, 2019**

(51) **LOC (12) Cl.** **14-01**

(52) **U.S. Cl.**

USPC **D14/206**; D14/226

(58) **Field of Classification Search**

FOREIGN PATENT DOCUMENTS

IN 310340-0001 * 9/2018

Primary Examiner — Paula Allen Greene

(57) **CLAIM**

The ornamental design for headphones, as shown and described.

DESCRIPTION

FIG. 1 is a perspective view of headphones showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof; and,

FIG. 8 is a bottom plan view thereof.

The broken lines in the drawings depict portions of the headphones that form no part of the claimed design.

1 Claim, 8 Drawing Sheets
